UNITED STATES PATENT OFFICE

ROBERT S. BLAIR, OF STAMFORD, CONNECTICUT

ART AND APPARATUS FOR GAMES

Application filed August 25, 1928. Serial No. 302,007.

This invention relates to an art and apparatus for games and, with regard to its more specific features, to improving the ease and accuracy of scoring in various games.

5 One of the objects thereof is to provide a simple and practical means for improving ease and accuracy of scoring. Another object is to provide means of the above nature of efficient and dependable action. Other 10 objects are to provide means of the above nature characterized by the lessening of delays; the increasing of certainty; the adaptability to a wide variety of games and to convenience in carrying the same on. Another 15 object is to provide a practical and convenient art for aiding in the attainment of the above results. Other objects will be in part obvious and in part pointed out hereinafter.

20 The invention accordingly consists in the features of construction, combinations of elements, arrangements of parts, and in the several steps and relation and order of each of the same to one or more of the others, 25 all as will be illustratively described herein, and the scope of the application of which will be indicated in the following claims.

In the accompanying drawing, in which is shown one of various possible embodiments 30 of the mechanical features of this invention,

Figure 1 is a diagrammatic plan of a baseball home-plate;

Fig. 2 is a diagrammatic illustration of the action of the apparatus;

35 Fig. 3 is a sectional elevation taken along the line 3—3 of Fig. 1 showing the parts on an enlarged scale;

Fig. 4 is a sectional plan taken along the line 4—4 of Fig. 3; and

40 Fig. 5 is a diagrammatic plan of wiring connections.

Similar reference characters refer to similar parts throughout the several views of the drawing.

45 Referring now to Fig. 1 of the drawing, there is shown by way of illustration of an embodiment of the invention, a home-plate 10 for use in the game of baseball. As is well known, the ball must pass vertically 50 above this plate in order to constitute a

“strike”. In certain locations, and particularly under certain conditions of light, it is difficult to ascertain whether or not the ball in transit has passed over the plate when its travel is nearly over one of its lateral 55 edges.

Referring now to Fig. 3 of the drawing, there is shown a portion of the plate 10 provided with an aperture 11 and having secured within said aperture the upper reduced end 60 12 of a casing 13 which may be bolted as at 14 to the under surface of the plate and extend downwardly into the ground. Within this casing is mounted an electric light bulb 15 preferably having an elongated filament lying substantially at the focal axis of a reflector 16 which is parabolic in cross-section and which would thereby tend to throw upwardly a sheet of parallel rays. These rays strike a suitable lens 17 and are condensed 70 upon a lens 18 of such form as to discharge the rays vertically upwardly in parallel relation and of a much greater density than when they strike the lens 17. There is thus thrown upwardly from the lens 18 a much-concentrated parallel-ray beam of light 75 which is preferably slightly wider in a direction transverse of the plate 10 than it is in a direction longitudinal thereof. This beam is intended to strike the under surface of a ball passing directly thereover, and it is of such thickness in the direction of travel of the ball as to illuminate a substantial part of the end surface so as to permit the illumination to be readily seen. The elongation in a 80 direction transverse to the plate is to cause this illumination of the ball whenever it is near the edge and thus greatly aid in determining whether the ball has passed over the plate when its transit is in the neighborhood 85 of the vertical plane through the side of the plate. It is so positioned with respect to the edge that whenever the lower surface of the ball is illuminated by the beam, the travel of the ball constitutes a “strike”.

It is understood that one of these illuminating devices is positioned at each side of the plate receiving light from a single lamp, if necessary, by suitable reflectors. It is also 100 to be understood that the beam of light, while

greatly concentrated to be of a high intensity, is nevertheless of a small cross-section as is permissible with effective illumination of the under surface of the ball.

In order to prevent obscuring of the beam of light by the collection of dirt upon the lens 18 and in order to remove dirt effectively from the upper surface of a home-plate and thus permit it to be more readily seen by the pitcher and umpire, there is shown in Fig. 3 of the drawing a casing 19 buried in the ground, as is the case with casing 18, and preferably positioned at one side thereof. In this casing is mounted an electric motor 20 driving a fan 21 which may draw air through a duct 22 from an intake 23 at any desired distance. The discharge of the fan passes through a conduit 24 and thence to a thin and laterally elongated nozzle 25. The flat wide jet of air discharged through said nozzle upon the operation of the motor not only cleanses the dust and dirt from the upper surface of the lens 18, but also from the adjacent upper surface of the plate near its lateral edges, and it is to be understood that although this feature is of particular advantage in combination with the remaining features of applicant's invention, nevertheless it is of value in use independently thereof in providing a means for cleansing the upper surface of a home-plate.

Both the lamp 15 and the motor 20, as diagrammatically indicated in Fig. 5 of the drawing, are provided with circuits leading to any desired source of supply, such as the mains 26. These circuits are respectively under manual control by the switches 27 and 28, it being understood that the switch 28 is closed whenever it is desired to cleanse the upper surface of the plate and the switch 27 may either be left closed throughout the game or any portion thereof or may be under control of the umpire and closed only during the transit of the ball. It will also be understood that the term "cleanse" is used throughout in a broad sense to denote the partial or complete removal of foreign matter, and that the term "jet" is also broadly used to denote any discharge of a fluid.

In the use of the above illustrative apparatus, it will be understood that the game is carried on in the ordinary manner but that whenever the ball, diagrammatically indicated at 29 in Fig. 2 of the drawing, passes through one of the planes 30 in such manner as to render it doubtful whether it is a so-called "strike" or a so-called "ball", then if it has in fact passed over the plate, the flash of illumination of its lower side would give evidence of such fact. It is also to be noted that even though it be comparatively light upon the field, nevertheless the upwardly projected beam of light strikes the ball upon its lower and darkest portion which much enhances the ease of use and certainty of action. If

dirt has collected upon the plate or upon one of the lenses 18 or both, the switch 28 is closed for a brief interval of time, whereupon the upper surface of these parts is cleansed by the resultant jet of air.

As various changes might be made in the features of construction above described, and as the mechanical features of this invention are susceptible of embodiment in various types of apparatus, and as the art features of this invention might be carried on with apparatus of other form, it is to be understood that all matter herein described or shown in the accompanying drawing is to be interpreted as illustrative and not in a limiting sense.

I claim:

1. In apparatus for games and the like, in combination, an objective apparatus adjacent which projectiles travel, means adapted to throw light in a direction to illuminate projectiles passing over said objective, and means adapted to confine said light into a pair of parallel beams vertically positioned at the lateral extremities of said objective. 85

2. In apparatus for games and the like, in combination, an objective apparatus toward which projectiles are discharged in a game, means adapted to throw vertically upward a beam of light from said objective, and means mounted adjacent said objective apparatus and coacting therewith adapted to remove dirt interfering with the transmission of said light. 95

3. In apparatus for the game of baseball, in combination, a home plate, and means adapted to throw a beam of light one edge of which extends substantially vertically in line with a lateral extremity of said plate. 100

4. In apparatus for the game of baseball, in combination, a home plate, and means adapted to throw light upwardly from substantially the level of said plate with substantially parallel rays, two edge portions of said light extending substantially vertically 110 upward respectively in line with the two lateral extremities of said plate. 110

5. In apparatus for games and the like, in combination, means indicating the lateral limits of a predetermined upright and laterally limited plane through which a body is to pass in the course of the contest, a source of light, and means for throwing a sheet of light in said plane from said source arranged and adapted to illuminate momentarily a portion of said body passing therethrough and thereby indicate its passage. 115

6. In apparatus for games and the like, in combination, means indicating the lateral limits of a predetermined upright and laterally limited plane through which a body is to pass in the course of the contest, means adapted to emit light and means deriving light therefrom adapted to throw light upwardly in a pair of parallel beams, the sub- 125 130

stantially parallel outer edges of which substantially coincide with the lateral limits of said plane, and by momentary illumination of a body passing therethrough indicate its course with respect to said plane.

5 In testimony whereof, I have signed my name to this specification this 23rd day of August, 1928.

CERTIFICATE OF CORRECTION.

Patent No. 1,868,088.

July 19, 1932.

ROBERT S. BLAIR.

It is hereby certified that error appears in the printed specification of the above numbered patent requiring correction as follows: Page 2, line 130, claim 6, strike out the word "parallel", and page 3, line 1, strike out the word "outer"; and that the said Letters Patent should be read with these corrections therein that the same may conform to the record of the case in the Patent Office.

Signed and sealed this 2nd day of May, A. D. 1933.

(Seal)

**M. J. Moore,
Acting Commissioner of Patents.**
